UNITED STATES PATENT OFFICE

2,613,332

ELECTRIC DISCHARGE DEVICE

Elmer D. McArthur, Schenectady, N. Y., assignor
to General Electric Company, a corporation of
New York

Application July 14, 1949, Serial No. 104,772

6 Claims. (Cl. 315—5)

1

This invention relates to improvements in electrical discharge devices and, in particular, relates to improvements in high frequency electrical discharge devices useful in high frequency electrical apparatus such as described and claimed in my copending application, Serial No. 751,358, filed May 29, 1947 and entitled "Electric Discharge Devices and High Frequency Systems Thereof," now abandoned in favor of continuation-in-part application Serial No. 10 179,854, filed August 16, 1950.

In the aforementioned application, I have described and claimed high frequency electrical systems useful as oscillators, amplifiers, reactance devices and the like and which employ grid controlled electron discharge devices as elements for controlling the energy which is associated with a resonant circuit. It is a general object of the invention claimed in any aforesaid application to provide an improved system characterized by a number of advantages such as more convenient and relatively wide band frequency control, a more convenient amplitude control and structural simplicity resulting from the fact that the number of resonant circuits heretofore normally required to be associated with the discharge device may be reduced, for example, by elimination of the resonant circuit heretofore normally associated with the cathode grid circuit of the device.

It is a general object of the device herein claimed to provide improvements in electron discharge devices and, in particular, to provide improvements in electron discharge devices of the character described in my aforementioned application.

Electron discharge devices used in certain apparatus, such as in radiosondes or in detonating fuses, operating in the high frequency range of the electromagnetic spectrum, must be capable of being quickly readied for operation from an inactive or quiescent state, in response to a controlling intelligence. Prior art electron discharge devices suitable for the generation or amplification of high frequency signals, such as devices of the magnetron or klystron classes, employ indirectly heated cathodes which take several minutes to become heated and readied for operation. Because they take such a long time to heat up, they are not at all suited for the abovementioned purposes. In addition to requiring the use of an indirectly heated cathode, these prior art devices are rather bulky and complicated in structure and operation and, thus,

5 their utility is further limited in expandable apparatus of the above-mentioned character. Electron discharge devices used in radiosondes and detonating fuses must operate on small amounts of power, since batteries are the usual source of power for devices in these applications.

10 Therefore, it is another object to provide an electron discharge device for use in the high frequency range of the electromagnetic spectrum which is quickly readied from an inactive or quiescent state to a state of operation and which requires a minimum of power to operate.

15 It is also an object to provide an electron discharge device for use at high frequencies that is simple to construct and requires a minimum of components.

20 It is a further object to provide an improved generator of high frequency electromagnetic energy that is immediately readied for operation from an inactive or "cold" condition in response to a directing intelligence which connects operating power to the electrode structure of the generator.

25 It is a further object to provide an improved high frequency oscillator which is simple to construct and operate, which is light and compact, and which requires a minimum of power to operate.

30 In general, the foregoing objects and advantages are achieved by constructing an electron discharge device with a directly heated filamentary cathode in which the control grid associated with the discharge device is utilized as a return heater power lead for the filamentary cathode. This construction not only eliminates a power return lead in the device by use of the grid as the power return lead, but also results in the advantages set forth above.

35 The features of the invention desired to be 40 protected are set forth in the appended claims. The invention itself, together with further objects and advantages thereof, may best be understood by reference to the following specification taken in connection with the single figure of the drawing wherein is shown a perspective view, in section, of an electron discharge device embodying my invention.

45 Before proceeding to explain my invention, a brief explanation as to the operation of apparatus of my aforementioned application is worthy of consideration. As is well known in the art, it is a common practice to employ multi-electrode electron discharge devices such as triodes having an anode, cathode and control grid as oscillators 50 by the expedient of providing a feedback circuit

between an anode-grid resonant circuit and a cathode-grid resonant circuit. The function of such a feedback circuit is to derive a small oscillatory signal voltage from the anode-grid circuit and employ it to energize the cathode-grid circuit in order that oscillations may be sustained by the amplifying effect on that signal voltage effected by the control grid of the device in the manner well known in the art. Generally speaking, the objects of the invention claimed in my aforementioned application, Serial No. 751,358, are accomplished by eliminating the necessity of the cathode-grid resonant circuit and, consequently, also the necessity of feedback circuits. In accordance with the principles of the invention of the aforementioned application, this result may be reached with an oscillator employing a multi-electrode discharge device, such as a triode having an anode, a cathode, and a control grid, and using space charge control of current flow in a manner similar to prior art oscillators, by reducing the high frequency impedance between the grid and the cathode to a very low value, preferably as near to zero as possible, whereby the latter two electrodes are maintained at essentially the same high frequency potential during operation. To that end, a large by-pass capacitor may be built into the discharge tube structure between the grid and the cathode or a direct connection may be made between grid and cathode. In addition, the interelectrode spacings are chosen to meet specific requirements for electron transit time, which requirements are indicated more fully in the aforementioned application.

With the arrangement described in the preceding paragraph, it becomes possible to generate oscillations with a circuit consisting of a single resonant circuit, such as a cavity resonator between the anode and either the grid or the cathode. Oscillations may be initiated as soon as a predetermined minimum voltage is exceeded on the anode of the device. Those oscillations will have a frequency primarily determined by the characteristics of the cavity resonator or other equivalent resonant circuit and their frequency and amplitude may be further controlled by a unidirectional bias voltage applied to the control grid. The net result is that an oscillator of considerably simplified construction may be provided which has additionally the advantage that it may be caused to oscillate in a more controllable manner throughout a wider continuous range of frequencies and amplitudes.

With reference to the invention of this application, which is embodied in an oscillator shown in the figure of the drawing, the provision of a filamentary cathode in the oscillator and utilization of the grid as a heater power return lead for the filamentary cathode result in further simplicity of construction and operation, in addition to realizing a device which is readied for operation quickly in response to a controlling intelligence, and which requires a minimum of power to operate.

Referring now to the single figure of the drawing, my invention is shown embodied in an electron discharge device 1 used as a generator of electromagnetic oscillations. In this figure is shown a cathode 2 supplying the electronic current, a control grid 3 and an anode 4. The grid is connected to the cathode for the high frequencies at which the device is to operate, at one end by direct connection 5, at the other end by a bypass capacitor 6 having substantially zero re-

actance at the frequency of operation. With the cavity member 7, the device functions as a simple, useful and effective generator of high frequency electromagnetic oscillations when the cathode 2 is suitably heated by a power source 8 and a suitable source 9 of power is connected between the anode 4 and the cathode 2 and grid 3 as a high frequency unit.

Referring now to the particularities of the grid-cathode electrode structure of the device 1, in order to provide an electron discharge device that can be immediately readied for operation and also which requires a minimum of heating power, a directly heated cathode 2 is used. The directly heated cathode 2 may take a variety of convenient and suitable forms. In the embodiment shown in the figure, a molybdenum tungsten alloy, which has been copper plated and thence coated with barium oxide may be used. This particular structure in filamentary cathodes is well known to those skilled in the art. In order to heat the cathode, it is necessary to connect electric power leads 10 and 11 to each end of the directly heated cathode. It is feasible enough to connect a power lead 11 to the filamentary cathode 2 at the end adjacent the "plug-in" end of the discharge device 1, but supplying power to the remote end of the cathode 2 presents difficulties. If a power lead is brought out at the end 12 of the discharge device 1, it presents mechanical constructional complications, difficulties and inconveniences, as well as resulting in a serious impairment in the electrical operation of the circuit. Further, if a lead from the other end of the filamentary cathode 2 is brought down through the inter-electrode space between the grid 3 and cathode 2 or between the grid 3 and anode 4, it seriously affects the field configuration within the discharge device and, hence, its operation. In order to overcome these difficulties, I have provided that the control grid 3 of the discharge device, which normally serves only a control function in devices of this character, also performs the function of supplying the means whereby the source of electrical power 8 to the cathode may be connected to remote end of the directly heated cathode 2. Thus, the remote end of the cathode 2 is connected to the heater power source 8 through member 5, grid 3, member 13 and lead 10. The end of the cathode 2 adjacent the "plug-in" end of the device is connected to the heater power source 8 through members 16, 14, 20 and 11. The direct connection of cathode 2 and grid 3 by conductive member 5 further improves the efficiency of devices of the character herein being described in that member 5 short-circuits the grid to the cathode directly. In devices of the character disclosed and claimed in my aforementioned application, it has been found that the efficiency and power output capabilities of the device are very substantially enhanced by reduction in the impedance between the grid and cathode connection. It should be noted that the end of the grid-cathode structure adjacent the "plug-in" end of the device is short-circuited for high frequencies by means of the capacitor 6 comprising plates 13 and 14 and dielectric 15.

The aforementioned grid-cathode structure may be incorporated in the electron discharge device 1 in various ways. In the figure, the cathode 2 is connected at one end through a spring tension member 16 to the cup-shaped support member 14, which also functions as the plate of bypass capacitor 6. The grid structure is supported by means of rod members 17 welded to the

grid structure; the ends of the rods are rigidly connected to flanged cup-shaped member 13. The cathode structure 2, along with the cup-shaped supporting member 14, is symmetrically located within the grid structure 3 and the flanged cup-shaped member 13. The free end of the cathode is conductively connected to the adjacent end of the grid by means of conductive member 5 as hereinbefore mentioned. The cup-shaped member 14 is supported within the flanged member by means of a silvered mica insulator 15. The members 13 and 14 with the mica insulator 15 comprise a capacitor which has substantially zero impedance at the frequency of operation of the device and, consequently, substantially short-circuits the grid 3 and cathode 2 at this end at these frequencies. It should be noted that with this structure, both ends of the cathode and grid are connected together by substantially zero impedance at the frequency of operation of the device.

The anode comprises a cup-shaped member 4 having a flange portion and is located preferably symmetrically with respect to the aforesaid cathode-grid structure. The member 4 is supported in place by means of vitreous member 18, which may be ceramic or any glass suitable for sealing to metal. The anode 4 may comprise any of a group of iron, nickel and cobalt alloys suitable for metal to glass sealing. The flanged portion of the anode member 4 is located in opposed relationship to the flange portion of the aforementioned cup-shaped member 13 with the flange portion of member 13 having a smaller diameter than the flange of member 4 to permit insertion of the device 1 in cavity member 7.

The support member 18 and the end wall 19 welded to the cup-shaped member 13 hermetically seal the active portions of the grid 3, cathode 2 and anode 4. Conductor 20, one end of which is connected to the member 14, permits connection of the cathode power source 8 to the cathode element 2. Vitreous member 21 suitably insulates conductive member 20 and, at the same time, makes a hermetic seal in the end wall 19. The tubulation 22 is used for the evacuation of the device 1.

In order to facilitate connection of the discharge device 1 to a cavity structure, flange member 21' is made with a larger radius than flange member 22'. The electron discharge device 1 is connected to the toroidal shaped cavity member 7 and held in place by means of clamps 23 and spring fingers 24 of the toroidal member. It is readily apparent that if the toroidal member 7 were a conductively continuous metallic member, the anode member 4 and grid member 3 would be short-circuited by this cavity. For this reason, a capacitor 25 is inserted between the upper and lower fingers 24 of the toroidal member 7 which make engagement with the upper and lower flange members 21' and 22', respectively. This capacitor comprises plate members 26 and 27 and silver mica dielectric 28. In order to strengthen mechanically the connection between member 26 and member 27, suitable fasteners 29 are placed around the periphery of the toroidal member 7 as shown. These fasteners may comprise a screw member 30 and a nut member 31 joining members 26 and 27 and insulated therefrom by means of flat dielectric washers 32 and 33 and sleeve washers 34.

By connection of a source 8 of heater power to the cathode by means of conductors 10 and 11 and by the connection of a source 9 of anode pow-

er between the cathode 2 and anode 4, as shown, the device may be readied for operation. Immediately upon the application of heater power to the cathode and the application of an electric potential between cathode and anode by the closing of switches 35 and 36, respectively, in response to a controlling intelligence, the device is immediately readied for operation to develop high frequency electromagnetic oscillations for whatever purpose desired. By immediately is meant a duration of time of a few seconds. The high frequency energy may be readily obtained from the cavity by means of a coupling member such as coupling loop 37.

While I have shown and described particular embodiments of my invention, it will be obvious to those skilled in the art that various changes and modifications may be made without departing from my invention in its broader aspects and I, therefore, aim in the appended claims to cover all such changes and modifications as fall within the true spirit and scope of my invention.

What I claim as new and desire to secure by Letters Patent of the United States is:

1. An electron discharge device for use at high frequencies comprising an anode, a grid and a cathode, said cathode including a directly energizable filamentary member, said grid including a structure symmetrically surrounding said cathode, means connecting one end of said cathode directly to the adjacent part of said grid structure, means connecting the other end of said cathode to said grid structure and forming a low impedance path between said cathode and said grid at the frequencies of operation of the discharge device whereby said cathode and grid operate essentially as a high frequency unit, and resonator structure connected between said anode and the essentially high frequency unit formed with said cathode and said grid.

2. An electron discharge device for use at high frequencies comprising an anode, a grid and a cathode, said cathode including a directly energizable filamentary member, said grid including a structure symmetrically surrounding said cathode, means connecting one end of said cathode directly to the adjacent part of said grid structure whereby said grid may be employed as a cathode heater return, means connecting the other end of said cathode to said grid structure and forming a low impedance path between said cathode and said grid at the frequencies of operation of the discharge device, and resonator structure connected between said anode and said grid.

3. An electron discharge device for use at high frequencies comprising an anode, a grid and a cathode, said cathode comprising a directly heated filamentary member, said grid comprising a structure symmetrically surrounding said cathode, means connecting directly one end of said cathode to the adjacent part of said grid structure and means connecting the other end of said cathode to said grid structure and forming a low impedance path between said ends of said cathode and said grid at the frequencies of operation of the discharge device.

4. An electric discharge device comprising a cup-shaped anode member, a directly heated filamentary cathode member located within said anode member, a control grid member located between said anode and cathode members, means directly connecting adjacent ends of said cathode and grid members at the end remote from the opening of said anode member, means con-

7
nected to the other ends of said cathode and said grid for supplying energization to said cathode, and resonator structure connected between said anode and said grid.

5. Electrode structure for use in high frequency electric discharge devices comprising a directly heated filamentary cathode and a grid symmetrically surrounding said cathode, means conductively connecting one end of said cathode to the adjacent end of said grid, reactive means substantially short-circuiting the other end of said cathode to the other end of said grid at the frequencies of operation of said discharge device.

6. Electrode structure for high frequency electromagnetic apparatus comprising a directly heated filamentary cathode, a grid surrounding said cathode, means conductively connecting one end of said cathode to the adjacent end of said

grid, a capacitor having substantially zero reactance at the frequencies of operation of the electromagnetic apparatus interconnecting the other ends of said cathode and said grid, means connecting the plates of the said capacitor to a source of heater power for the cathode.

ELMER D. MCARTHUR.
